UNITED STATES PATENT OFFICE.

FRANCOIS VICTOR ALBERT THOMAS, OF PARIS, FRANCE.

CARBURETOR.

Application filed February 14, 1921. Serial No. 444,862.

To all whom it may concern:

Be it known that I, FRANCOIS VICTOR ALBERT THOMAS, a citizen of the French Republic, and resident of Paris, France, have 5 invented certain new and useful Improvements in Carburetors, of which the following is a specification.

This invention relates to carburetors for internal combustion engines using a gaseous 10 fuel formed from a heavy fuel oil.

An object of the invention is to utilize gaseous fuel from a heavy oil and reduce the temperature before the entrance thereof into the combustion chamber to a point 15 slightly above the condensation point of the particular oil, and to mix it during the cooling thereof with the necessary charge of atmospheric air immediately preceding its entrance into said combustion chamber.

20 In all engines using heavy fuel oil, it is necessary to vaporize the oil before it is mixed with air and passed to the combustion chamber, which necessitates the heating of the fuel to a relatively high temperature.

25 At this high temperature, the fuel vapor is considerably less efficient in the operation of the engine and with the use of the present invention, the fuel vapor is cooled slightly before and at the time of 30 its mixture with a charge of atmospheric air to a point slightly above the condensation temperature of the vapor, so that the charge entering the combustion chamber is at a relatively low temperature in order 35 that the greatest efficiency from a certain quantity of fuel oil can be obtained.

In carrying out the above features, the invention includes the use of a mixing tube having one end secured directly on the engine block over the intake therein, and the other end provided with a valve-controlled air inlet, a fuel vapor inlet entering the mixing tube a short distance from the engine block, and a jacket surrounding the 45 mixing tube and fuel vapor supply pipe for the circulation of a medium therein for conditioning the air in the mixing tube and the fuel vapor, so that as they are mixed in the tube, the medium in the jacket will 50 change the temperature of both the gas vapor and the air to bring it to a point slightly above the condensation temperature of the fuel vapor, at which time the mixture immediately passes into the cylinder by reason 55 of the close proximity of the point of mixing with the chamber, so that no appreciable

change can take place before the mixture enters the chamber.

Other features and the details of construction and operation of the invention are 60 pointed out in the following description and claims.

In the drawings:

Fig. 1 is a diagrammatic sectional view 65 of the carburetor.

Fig. 2 is a diagrammatic view illustrating the application of a single carburetor to an engine having a plurality of cylinders.

Fig. 3 is a diagrammatic sectional view 70 of the modified form of the invention.

1 indicates the mixing tube of the carburetor having a flange 2 which is attached to the engine block adjacent the intake valve. A pipe 3 leading from a heavy fuel oil vaporizer terminates in the head 4 centrally disposed in the mixing tube and having a nozzle 5 thereon governed by a valve 6 which is connected through a stem 7 for operation with a valve 8 governing the inlet of atmospheric air to the mixing 80 tube.

A jacket 9 surrounds the mixing tube and is provided with an extension portion 9' extending around the pipe 3, a fluid inlet being provided at 10 for a cooling fluid 85 which circulates about the mixing tube in the pipe 3 and is exhausted through an outlet in the extension 9'.

The heavy fuel vapor passing through the pipe 3 is gradually cooled by the cooling medium in the jacket extension 9' until it flows from the nozzle 5 where it is mixed with atmospheric air entering the tube 1 around the valve 8, which is cooled by the cooling medium in the jacket 9 and then 95 in this cooled state immediately enters the combustion chamber by reason of the positioning of the carburetor adjacent the intake valve. In this way, the cooling of the fuel vapor and the charge of air mixed 100 therewith in the mixing tube 1 can be accurately governed to prevent the cooling of the vapor to the condensation point and at the same time get a sufficient cooling to obtain the maximum volumetric efficiency in 105 the combustion chamber, the close proximity of the mixing tube being of material importance in the use of this device, in order that the mixture cannot come in contact with intervening elements which might 110 affect the temperature before it enters the combustion chamber.

In Fig. 2, the carburetor structure as shown in Fig. 1 is indicated at 11 and a mixture carrying a pipe 12 extends from the carburetor and is formed with branches 13 which communicate with the cylinders at two different points. A jacket 14 surrounds the branches 13 and a jacket 15 connects the ends of the jacket 14 with the jacket around the carburetor. Flanges 16 are secured to the jacket and the ends of the branches 13 pass through these plates into the cylinders, the plates being fastened to the engine block. In this structure, the cooling medium circulates around the carburetor and thence in each jacket 15 around and through the jacket 14 and out through outlet pipes 17. In this construction the cooling is effected subsequent to the mixing of the air and fuel vapors, the principal 20 cooling being effected as the mixture passes through the branch pipes 13.

In Fig. 3, the air intake is shown at 18 and the fuel vapor inlet at 19 entering the air intake at one side as shown at 20, the air 25 intake being formed with a flange 21, which is secured to the engine block so that the mixture will immediately pass into the cylinder. The fuel vapor is cooled before it is mixed with the air by a cooling medium 30 circulating in a jacket 22 surrounding the fuel vapor inlet 19, the inlet to the jacket being located at 23 and the outlet at the opposite end of the jacket beyond the portion broken away.

From the above it will be seen that the preferred form of the device shown in Fig. 1 is located so that the mixing of the fuel vapor and air takes place immediately preceding the entrance into the cylinder, and that at the point of mixing, the fuel vapor and the air will be at a relatively low temperature to provide for the maximum efficiency in the engine, the temperature being relatively unchanged in the passage of the mixture from the mixing tube to the combustion chamber due to the close proximity of one to the other, which enables the temperature at the mixing point to be accurately controlled so that the fuel vapor may 45 be cooled to a point only a few degrees above the point of condensation thereof. This same principle is carried out in the device shown in Fig. 3 with the use of a slightly different form of carburetor, and 50 in the structure shown in Fig. 2 a similar result is produced in first mixing the vapor and air and subsequently cooling it before it enters the combustion chamber.

What I claim is:

1. A carburetor comprising a mixing tube having an air inlet at one end thereof and a flange at the other end adapted for attachment to an engine block, a fuel vapor

inlet extending into the mixing tube and having a valve governed outlet therein, and 65 a jacket surrounding the carburetor and fuel vapor inlet for permitting the circulation of a cooling medium about the mixing tube and fuel vapor inlet, whereby said vapor may be cooled to a point slightly 70 above its temperature of condensation at a point in close proximity to the combustion chamber of an engine.

2. A carburetor comprising a mixing tube having an air inlet at one end and adapted 75 for connection to the engine cylinder at the other end, a fuel vapor outlet extending into said mixing tube and having an outlet therein, interconnected valves for governing the fuel vapor outlet and the air inlet 80 for proportioning the mixture of air and fuel vapor, and a cooling jacket surrounding the mixing tube and fuel vapor inlet, whereby the fuel vapor is cooled before it enters the mixing tube, the air is cooled 85 before it contacts with the fuel vapor so that the mixture is cool when mixed and immediately enters the engine cylinder for producing a high efficiency combustion.

3. A carburetor comprising a mixing tube having one end formed with a flange whereby said tube may be secured directly to an engine block over the intake port 90 therein, and the other end provided with a valve-controlled air inlet, a fuel vapor inlet 95 entering the mixing tube adjacent the engine block having a valve-controlled outlet therein, and a jacket secured to and surrounding the mixing tube and the fuel vapor inlet for receiving a cooling medium 100 for changing the temperature of the air and the fuel vapor as it is mixed in the tube to a point slightly above the condensation temperature of the fuel vapor, whereupon the mixture immediately enters the combustion chamber due to the close proximity of 105 the mixing chamber thereto.

4. In a carburetor, an atmospheric air admission duct, a mixing chamber, means for regulating the amount of air to be admitted to the mixing chamber, a duct for the admission of fuel vapors to the mixing chamber, means for regulating the amount of fuel vapors to be admitted, a member connecting both regulating means, and a 110 cooling fluid jacket surrounding the atmospheric air admission duct, the mixing chamber, and a portion of the fuel vapor admission duct.

In testimony whereof I have hereunto set 115 my hand in presence of two witnesses.

F. V. ALBERT THOMAS.
